UNITED STATES PATENT OFFICE.

NICHOLAS V. MAZZOCCHI, OF NEW YORK, N. Y.

GAS-BURNER.

1,314,686.

Specification of Letters Patent. Patented Sept. 2, 1919.

Application filed January 16, 1919. Serial No. 271,365.

To all whom it may concern:

Be it known that I, NICHOLAS V. MAZZOCCHI, a citizen of the United States, and resident of the city of New York, in the county of New York and State of New York, have invented certain new and useful Improvements in Gas-Burners, of which the following is a specification.

This invention relates to burners operating by a fluid fuel used in connection with stoves or ranges.

My main object is to provide a burner of this character in which all outlets receive a substantially equal share of the fuel supply, so that they all burn with substantially equal intensity.

Another object is to provide in a burner of this character means for directing a flame against a particular desired portion of the stove or range without interfering with the burning of the other pipes of the burner and without reducing the efficiency of the burner as a whole.

A further object is to provide a burner of the character described which shall be simple and cheap in construction and uniform, efficient and economical in operation.

A still further object is to provide in a burner of this character an outlet pipe which shall be cheap to manufacture and adapted to be directly fitted to the nipple without tapping or threading.

A further object is to provide a burner of the character described which shall economically and efficiently permit of the burning of one or several complete rows of pipes independently of the others.

Other objects and advantages of this invention will appear from the detailed description and the features of novelty will particularly be pointed out in the claims:

In the drawing accompanying this specification and forming a material part thereof,

Figure 1, is an elevational view of a range provided with an embodiment of my invention, parts being broken away;

Fig. 2 is a partly broken away section cut along line 2-2 of Fig. 1;

Fig. 3 is a detailed section cut along line 3-3 of Fig. 2 and showing the particular construction of the mixing chamber whereby uniformity of intensity and burning is obtained;

Fig. 4 is a detailed section cut along line

4-4 of Fig. 2 showing the sectional construction of my improved burner, and the means for directing the flame against a particular portion of the stove without interfering with the operation of the remaining burners.

Referring in detail to the drawing I have there shown a range 15 of the French type having the fire pot 16 and the oven 17.

My burner is secured within the range by any suitable means such as the brackets 18, and is made up in separate sections comprising end mixing chambers 19, the central chamber 20, and the intermediate chambers 21. Extending from these chambers are the nipples 22 for the burner pipes 23. As will be clear from Figs. 3 and 4 these pipes are cast in one piece formed with a flanged connecting end 24 adapted to fit over the nipples. In practice an air tight joint may be obtained by applying a thin layer of cement on the inner surface of the connecting portion. This construction does away with the necessity of tapping the connecting end of the pipes and threading the nipple, and thus affords a great saving in labor and expense.

The end sections 19, are made sloping at the top as at 25 and the nipples 22' extend therefrom at a gentle angle so that the end rows of burners 23' project a flame against the walls 26 of the oven. It will be noted that the directing of the flame against the walls of the oven is accomplished by a principal and independent row of burner pipes, and not by branch pipes at an angle to a main line of burners. The latter construction has been resorted to but found inefficient so that the fuel supply divides itself very unequally between the main and branch pipes. The central burners are vertical and heat directly the heat retaining balls shown at 27. I preferably mold these heat retaining balls in one cluster made up of continuous rows as shown. This is preferable to supporting individual balls on rods, as has been done heretofore, since the rods soften under the heat and stay together with the balls.

I am aware that to thus direct the flame at an angle against the walls of the oven is not new but in constructions heretofore made this has been accomplished at the expense of a reduced fluid pressure for the remaining burner pipes which prevented

them from burning properly. In the present invention this difficulty is obviated by the independent sectional construction.

To further assure that all of the burner pipes in a given section will receive a substantially equal pressure supply, I give the mixing chamber the construction shown in Fig. 3. As will be clear from this figure the typical mixing chamber is formed with an enlarged front portion having an opening 29 for the fuel supply and a narrowed rear portion 30 thus providing a baffle wall 31. In the constructions heretofore had the mixing chamber has been made substantially rectangular in form and as the fuel comes in under the pressure, it is first forced against the rear end of the chamber so that only a few pipes take up more of the supply while the front burners burn with a low flame if at all. In the improved construction the pressure first becomes incident on the baffle wall 31. The fuel under the pressure is then reflected and distributed equally among the burners of the section.

From Fig. 2 it will be obvious that I make my end sections 19 preferably L shaped and the intermediate sections 21 shorter than the central section 20. The elbow of the L is made to carry an extra pipe which together with the burners of the shorter section form a row of burner pipes of the same number as that in the central section. In this way the burners may be operated independently of the others and without taking up too much space or material. As will be clear the back burner on the L may be operated although the remaining burners in

the shorter section are shut off. The sections may be held together by any suitable means such as the straps 32 and the dowels 33.

Having thus described my invention, I claim:—

1. A burner comprising a plurality of sections constituting mixing chambers, the central section being of greater length than the intermediate sections and the end sections being shaped so as to be disposed alongside and across the end of said intermediate sections so as to complete the length of the latter equal to that of the central sections.

2. A burner comprising a plurality of sections constituting mixing chambers and embracing a central section, shorter intermediate section and substantially L-shaped end sections adapted to complete the length of said shorter side sections equal to the length of said central sections.

3. A burner comprising a plurality of sections constituting mixing chambers, said mixing chambers comprising a wide portion terminating in an inclined wall adapted to serve as a baffle and a narrower tapered portion extending from said wall, the central section being of greater length than the intermediate sections and the end sections being shaped so as to be disposed alongside and across the end of said intermediate sections so as to complete the length of the latter equal to that of the central sections.

Signed at New York city in the county of New York and State of New York this 16th day of August A. D. 1918.

NICHOLAS V. MAZZOCCHI.
